BRUSH CLEANER

Filed Feb. 9, 1931

Fig. 3.

Inventor
Henry Fuhr
By Amold Eichler
Attorney

UNITED STATES PATENT OFFICE

HENRY FUHR, OF WAUKESHA, WISCONSIN

BRUSH CLEANER

Application filed February 9, 1931. Serial No. 514,568.

This invention relates to a brush cleaner and more particularly to a device whereby a clothes brush or the like may be readily cleaned, when the brush is moved with a reciprocal movement over the cleaning device, and the bristles of the brush having contact with the top surface of the device.

One of the objects of the invention is to provide a brush cleaner having a plurality of corrugations over which a strip of paper may be readily clamped, whereby when a brush is moved over and in contact with the paper covered corrugations, the dust from the brush will adhere to the paper.

Another object is to provide a spool of paper or the like which may be readily unwound a sufficient length to cover the corrugated surface, and the end of the paper attached to a second spool, and to provide means whereby a soiled strip of paper may be wound upon said second mentioned spool and a clean strip unwound into operative position, from the first mentioned spool.

Another object is to provide means whereby the spools may be readily removed from their bearings and replaced.

I have found that the dust brushed from clothes adheres to the ends of the brush bristles in somewhat of a layer and will readily adhere to another surface and it is one of my main objects to provide a plurality of corrugations for breaking up this layer, so that the same may more readily be removed.

Other objects will appear in the following specification and accompanying drawings in which

Figure 1 is a longitudinal sectional view,

Figure 2 is a top plan and

Figure 3 is a detail cross section.

In the drawings 1 indicates a casing having a top wall 2, end walls 3 and 4, and side walls 5 and 6.

Bent inwardly of the end walls 3 and 4 are the flanges 7 to provide support for the casing 1.

Arranged within the frame 1 and pivotally carried upon suitable bearing are spools 8 and 9. Carried by the spool 8 is a roll of paper or the like 8' which has its free end threaded thru an opening 10 in the wall 4 a

sufficient length to completely cover the top wall 2 and then threaded thru the opening 11 in the wall 3 and attached as at 12 to the spool 9.

Formed in the top wall 3 are a plurality of corrugations 13.

Pivottally carried in the bearings 14 is a clamping frame 15 which in the present instance comprises a pair of tubular side rods 16 and 17 and cross rods 18.

After a section of the roll of paper 8' is unwound whereby to cover the top wall 2 the frame 15 is rocked on the pivot pin 20 into clamping position as shown in Figure 1 and locked in position by the lock spring 21.

The device is then in operative position.

When a brush is to be cleaned it is moved in a reciprocal movement across the corrugated surface and in contact with the paper covering 22.

I have found that the dust accumulated on a clothes brush, after being used, rests on the ends of the bristles of the brush in a form of a layer, and when the brush in this condition comes in contact with corrugated surface 75 of my device, this layer is broken up and the particles of dust adhere to the paper covering, thereby cleaning the brush.

When the paper covering 22 becomes dirty, the clamping frame 15 is moved out of locked 80 position, and the soiled sheet of paper is wound upon the roller 12, by means of the crank 23, and by further movement of the crank 23, a clean sheet of paper is unwound from the roll 8', to be clamped into operative 85 position upon the corrugated surface.

The corrugations 13 are arranged in the present instance on an arc, whereby when a brush is moved over this surface in a reciprocal movement, different depths of the 90 bristles will engage the corrugations, thereby creating a greater tendency to the breaking up of the layer of dust on the brush.

It is to be understood that various changes may be made in the construction of my device without departing from the spirit of my invention except as limited by the scope of the appended claims:

I claim:

1. In a brush cleaner, a casing having a 100

corrugated top surface, a spool rotatably carried at one end within said casing, a roll of paper carried by said spool, a second spool rotatably mounted in said casing, a length of said paper unwound and adapted to cover said corrugated surface and having its free end attached to said second spool, and means for clamping said length of paper upon said corrugated surface.

2. In a device of the class described, a casing having a top plate, a curved corrugated top surface formed in said top plate, a sheet of paper adapted to cover said corrugated surface, a clamping frame pivotally mounted at one side upon said top plate for clamping said paper upon said corrugated surface, and a lock spring for locking said clamping frame in clamping position.

3. In a device of the class described, a casing having a corrugated top surface, a spool rotatably mounted at one end within said casing, a roll of paper carried by said spool, a second spool in said casing, a length of said paper unwound from said roll and adapted to cover said corrugated surface and having its free end attached to said second spool, means for releasably clamping said length of paper upon said corrugated surface, and a crank for winding said length of paper upon said second mentioned spool.

4. In a brush cleaner, a casing having a top wall, side walls, and end walls, a pair of spools rotatably carried by said side walls, a roll of paper carried by one of said spools, a corrugated surface formed in said top wall, an opening formed in each of said end walls, a length of paper unwound from said roll and threaded thru one of said openings and adapted to cover said corrugated surface, the free end of said length of paper threaded thru the other of said openings, a crank for winding said length of paper upon said second mentioned spool, and a clamping frame for releasably clamping said length of paper upon said corrugated surface.

In witness whereof I have hereunto set my hand this 18th day of December, A. D. 1930.

HENRY FUHR.
